(57) **CLAIM**

The ornamental design for a boat hoist side rail, as shown and described.

DESCRIPTION

A portion of the disclosure of this patent document, including appendices, may contain material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a perspective view of the boat hoist side rail, showing my new design;

FIG. 2 is an enlarged side elevational view of the side rail;

FIG. 3 is an enlarged top plan view thereof;

FIG. 4 is an enlarged bottom view thereof; and,

FIG. 5 is an enlarged end elevational view thereof, the opposite end being a mirror image thereof.

The broken line showing of environmental structure in FIGS. 1-4 is for illustrative purposes only and forms no part of the claimed design.
